UNITED STATES PATENT OFFICE.

EDWIN M. GOLDSMITH, OF PHILADELPHIA, PENNSYLVANIA, ASSIGNOR TO
FRIEDBERGER-AARON MANUFACTURING COMPANY, OF PHILADELPHIA,
PENNSYLVANIA, A CORPORATION OF PENNSYLVANIA.

HOLDER FOR ELASTIC AND SIMILAR GOODS.

1,183,003.

Specification of Letters Patent.

Patented May 16, 1916.

Application filed November 20, 1915. Serial No. 62,485.

To all whom it may concern:

Be it known that I, EDWIN M. GOLDSMITH, a citizen of the United States, residing at Philadelphia, county of Philadelphia, and 5 State of Pennsylvania, have invented a new and useful Improvement in Holders for Elastic and Similar Goods, of which the following is a full, clear, and exact description, reference being had to the accompanying 10 drawings, which form a part of this specification.

The object of my invention is to provide a holder for containing and exhibiting silk, elastic, tape, embroidery, lace, trimming, 15 edging, and similar goods.

The same comprises a container, a card within the same, and a flap cut out from the wall of the container and so located on the container and so arranged relatively to the 20 card, that the elastic, or other goods, while wound upon the card, will have a locking engagement with the flap and be exposed to view, the engagement also being such and the construction of the container such that 25 when the latter is opened, the card may be withdrawn and the elastic automatically disengaged from the flap in the process of withdrawal of the card.

A structure embodying my invention is 30 shown in the accompanying drawings, in which—

Figure 1 is a plan view of the holder with the front end open. Fig. 2 is a central section through Fig. 1. Fig. 3 is a plan view 35 of the card detached from the container.

The container is a box preferably of an oblong but nearly square form and of a depth shallow relatively to its length and width. One end of the box must be capable 40 of being opened, and for this purpose I show the bottom *a* of the box provided at the front end thereof with a double-fold flange *b*, and flanges *d*, *d*, on the front ends 45 of the narrow sides *c*, *c*, the flanges *b*, *d*, *d*, coöperating to form an end closure. This construction is one well known in the art. The rear end of the box, if desired, may be 50 provided with a similar closure *e*; but if the end closure *e* is provided there should be printed on the exposed fold of the flange *b* "To remove contents, open this end"—or words of similar import. The top *f* of the folder is cut or slit along the lines *x*, *y*, *z* to form a flap *g*, the flap being preferably

located relatively near the rear end of the 55 box, the hinge of the flap being located toward the rear and the free edge of the flap located toward the front.

The elastic or other similar goods *w* is wrapped spirally around a card *h*, opposite 60 ends of the elastic being preferably secured to the card. A part of one section of the elastic near the rear of the card extends out through slot *x*, across the face of the flap *g* and in through slit *y*. By this arrangement, although the elastic is supported wholly by the card, the card, and also the elastic, are locked to the container by the 65 engagement of the elastic with the flap *g*, and at the same time a small length of elastic 70 is exposed to view in order that the purchaser may be apprised of the contents of the box.

When it is desired to remove the elastic from the container, the front end closure is 75 opened and the card withdrawn. The withdrawal of the card being in a direction away from the hinged edge of the flap *g*, the latter offers no resistance to the removal of the card, the elastic slipping freely off its 80 free edge.

While boxes have been cut away to expose goods contained in the box, and while boxes have been provided with flaps on which the goods have been wound, and while goods 85 contained in boxes have been passed through slits in the box so as to expose a part of the same to view, they do not accomplish the object of my invention, which is to support the goods on a card independent of the container, which goods, while exposed to view, are locked to the container only when the container is closed, but which, when the container is opened, may be automatically 90 unlocked from the container and instantly 95 removed therefrom by simply withdrawing the card.

Having now fully described my invention, what I claim and desire to protect by Letters Patent is—

A holder for elastic and similar goods comprising a box of a depth shallow relatively to its length and width, the front end of the box having a removable closure and the top of the box being cut away to form 105 a flap hinged at its rear edge and free along opposite ends and its front edge, and a card within the container upon which the goods

are wound and adapted to support the goods independently of the container, a section of the goods on the face of the card adapted to extend over the flap from end to end, thereby, when the container is closed, locking the goods to the box and exposing a relatively small part thereof to view while permitting

the goods to automatically detach themselves from the flap when the card is withdrawn.

10

In testimony of which invention, I have hereunto set my hand, at Philadelphia, on this 18th day of November, 1915.

EDWIN M. GOLDSMITH.
